Application September 11, 1936, Serial No. 100,250
In Germany September 16, 1935

12 Claims. (Cl. 179—7.1)

The present invention relates to a circuit arrangement for remote communication systems and more especially to telephone systems for effecting two different speaking operations over

5 the same lead. It aims at effecting the switching operations in a manner which is always sure and free from objections with the minimum of additional auxiliary devices, and also at maintaining the one switching operation while promoting the 10 second switching operation.

15 The present invention affords special advantages in cases where over the one lead a connection is being held, for example an outgoing line, and another switching operation, for example metering, is to be effected.

20 A further advantage of the invention consists in that the new arrangement can be used without difficulty in systems already in existence since in this case the carrying out of all the switching operations is facilitated without considerably affecting the existing system merely by incorporating the necessary receiving devices and rectifiers for effecting the new switching operation.

25 The invention consists in that a rectifier is arranged in parallel with each of the two magnets which are connected in series and effect the switching operations, which rectifiers are arranged in the opposite sense with respect to one another, one of the operations being effected 30 without disturbing the first by means of alternating current.

35 Embodiments of the invention are shown in the drawings. The arrangement according to Fig. 1 relates to metering, in point of fact time metering, while the call is in progress.

40 In Fig. 2 another embodiment is represented in which definite signals are transmitted to a particular position during the establishment of a call by the arrangement according to the invention.

45 Fig. 3 shows an arrangement in which routing over a particular traffic direction is effected by means of the invention.

The detailed arrangements will now be described: In the interest of simplicity and clarity only those details which are necessary for explaining the invention are shown.

50 When the subscriber I_n in the arrangement according to Fig. 1 raises his receiver for the purpose of establishing a call the following circuit is set up: earth, winding of relay R, contact $1t$, subscriber's loop, contact $3t$, resistance W_{11} , battery and earth. Relay R energizing in this circuit closes its contact $8r$ and thereby completes the following circuit for the rotary magnet D of

the preselector VW: earth, battery, contacts $8r$ and $6t$, rotary magnet D, relay interrupter RU and earth. When the preselector has found a free first group selector IGW the following testing circuit is established: earth, battery, contact $7r$, windings II and I of relay T (in parallel with winding I of the meter relay Z which, however, does not energize in this circuit), wiper C of the preselector VW, resistance W_{13} , winding of relay C, off-normal contact $12k$, of the preselector (operated after the first vertical step) and earth, and in parallel over contact $13m$ of the release magnet of the group selector IGW and resistance W_{14} and earth. In this circuit relays T and C energize. On account of the closing of contact $5t$ 10 the high resistance winding II of relay T is short-circuited and thereby the group selector which has been seized is guarded against further seizure. By the opening of contact $6t$ the preselector is brought to rest. At contacts $1t$ and $4t$ the line of 15 subscriber I_n is switched through to the first group selector IGW. The following circuit exists for relay A in the first group selector IGW: earth, battery, winding of relay A, wiper a of the preselector VW, contact $1t$, subscriber's loop, 20 contact $4t$, wiper b of the preselector VW, resistance W_{12} , and earth. The first group selector IGW is now set in the known way by the calling subscriber, in that the impulse relay A transmits 25 a number of impulses, corresponding to the digit 30 transmitted, to the vertical magnet of the first group selector IGW. When the switch has been set on the desired level it searches to find a free second group selector IIIGW. When this is found the following circuit is established: earth, battery, 35 resistance W_{16} , winding II of relay C1, off-normal contact $23k1$ (open after the first vertical step of the second group selector), contact $18zr2$, wiper c of the first group selector IGW, winding I of relay P (whose short-circuit is removed by contact $14c$), winding II of relay P, contact $16c$ and earth. In this circuit the testing relay P of the first group selector IGW and the seizing relay C1 40 of the second group selector both energize. Current from the circuit thus mentioned cannot be 45 transmitted through the rectifier $G11$ arranged in parallel with winding I of relay P since it is non-conductive to current in this direction. Relay P closes contact $15p$ thereby establishing a short-circuit over the high resistance winding II of relay P so that the seized second group selector IIIGW is guarded against further seizure. The 50 guarding circuit passes from contact $15p$ over the rectifier $G12$ to earth. The rectifier $G12$ is connected up in the opposite sense to rectifier $G11$

and is conductive to current in this direction. Thus the rectifier $G12$ constitutes in practice a short-circuit for relay $ZR1$ and prevents this relay from energizing at the moment. Relay $C1$ was energized in the second group selector $IIGW$ and by opening contact $22c1$ removes a short-circuit existing over its winding I and by closing contact $21c1$ connects up this winding in preparation.

10 The calling subscriber now transmits the second numerical impulse train for setting the second group selector $IIGW$. This influences the impulse relay A in the first group selector IGW . On account of the intermittent release of this relay contact $9a$ is closed and opened a number of times thereby completing in a corresponding manner the circuit for the impulse relay $A1$ in the second group selector $IIGW$: earth, contacts $10c$ and $9a$, wiper a of the first group selector IGW , 15 rotary off-normal contact $17w$, (open after the first rotary step of the second group selector), winding of relay $A1$, battery and earth. Relay A transmits the impulses thus received to the vertical magnet (not shown) of the second group 20 selector $IIGW$. After this selector has been set on the desired level it hunts automatically for a free multiple meter set MZS . When this has been found the following testing circuit is established: earth, battery on the c -lead in the connecting 25 device arranged beyond the multiple meter set, winding of relay $C2$ in the multiple meter set MZS , contact $29h$, wiper c of the second group selector $IIGW$, windings I and II of the testing relay $P1$, rectifier $G14$, contact $25c1$ and earth. 30 The rectifiers $G13$ and $G14$ in the second group selector are arranged in a similar manner to the rectifiers $G11$ and $G12$ in the first preselector. The rectifier $G13$ is arranged in parallel with winding I of the testing relay $P1$ and is arranged so 35 that it is non-conductive to current flowing in the same direction as that in the circuit just described while the rectifier $G14$ is arranged in the opposite sense and thus will transmit current in this direction. The latter rectifier accordingly serves 40 to short-circuit relay $ZR2$ so that this relay cannot energize for the moment. Relay $C2$ has been energized in the multiple meter set MZS and by closing its contact $33c2$ prepares for the energization 45 of relay H .

50 The calling subscriber now transmits the remaining impulse trains and thus establishes the connection to the desired subscriber by setting further connecting devices beyond the multiple meter set.

55 When the called subscriber replies a circuit which may be closed in any known way is completed for relay B in the multiple metering set. Relay B closes its contact $32b$ and thereby connects relay H to the interrupter $U1$. The interrupter $U1$ is arranged so that it closes a contact at definite intervals of time, for example at intervals of one minute and each time causes relay H to energize; earth, interrupter $U1$, contacts $33c2$ and $32b$, winding of relay H , battery and earth.

60 Naturally if necessary interrupters can be used which close contacts at different intervals of time. Relay H closes its contact $26h$, $30h$, and $31h$ and opens its contact $29h$. By closing contact $26h$ battery is applied over contact $27zr3$ and resistance $W17$ which serves to hold energized devices connected to the c -lead in the previous connecting devices, i. e., in the second group selector. At contact $29h$ the holding potential applied in the devices arranged beyond the multiple metering 65 set is disconnected but the energization of relay

$C2$ of the multiple metering set and the devices connected to the c -lead in the following connecting device is maintained by the connection of earth at contact $30h$. By the closing of contact $31h$ the following circuit is completed for relay $ZR3$ in the multiple meter set: earth, contact $31h$, winding of relay $ZR3$, battery and earth. Through the opening of contact $21zr3$ the battery potential connected over resistance $W17$ is disconnected and by the closing of contact $28zr3$ (without breaking the contact) a source of alternating current (25 or 50 cycles) is connected over resistance $W18$. This alternating current flowing over the c -lead operates on the second group selector $IIGW$ in such a manner that alternate half waves of this alternating current passes over the rectifier $G13$ while the other half waves pass over winding I of relay $P1$. The half waves of this alternating current in one direction also pass over rectifier $G14$ while the other half waves pass through the winding of relay $ZR2$. The effect of this is that relay $ZR2$ in the second group selector $IIGW$ energizes during the connection of alternating current to the multiple meter set. Thus on the one hand the application of the alternating current serves to maintain the testing relay $P1$ energized in the second group selector GW and on the other hand serves to energize the meter repeating relay $ZR2$. If the contact is broken by the interrupter $U1$ in the multiple 30 metering set, relay H releases and restores the multiple metering set to normal condition, the source of alternating current being incidentally disconnected again. Accordingly on account of the short-circuit over relay $ZR2$ in the second 35 group selector $IIGW$ produced by the rectifier $G14$ this relay is caused to deenergize. Each time it energizes relay $ZR2$ opens its contact $18zr2$ and closes its contacts $19zr2$ and $20zr2$. At the last mentioned contact earth is connected 40 up thereby preventing relay $C1$ from releasing. By the closing of contact $19zr2$ a source of alternating current is connected to wiper c of the first group selector IGW over resistance $W15$. One half-wave of the alternating current passes 45 over the rectifier $G11$ and the other over winding I of relay P . Thus relay P remains energized during the application of the alternating current. The rectifier $G12$ which is conductive to the previous flow of current likewise receives one half-wave of the alternating current while the other passes through the winding of relay $ZR1$. Relay $ZR1$ is accordingly energized. It closes its contact $11zr1$ thereby giving rise to an increase in the current density over the guarding 50 lead from the preselector whereby the meter Z of the calling subscriber is advanced one step. On the termination of the application of the alternating current which is determined by the interrupter $U1$ in the multiple metering set MZS the 55 relays $ZR3$, $ZR2$, and $ZR1$ are deenergized again, relay $ZR3$ being deenergized by the opening of contact $31h$ and relays $ZR2$ and $ZR1$ by being short-circuited over the rectifiers $G14$ and $G12$. Thus the normal condition is once more established. In this way the meter Z of the calling 60 station is advanced step by step at intervals of time determined by the interrupter $U1$.

At the end of the call all the connecting devices are restored to the normal position. Since 70 these operations are well known and have nothing to do with the invention a detailed description need not be given.

In Fig. 2 an arrangement is shown by the aid of which a subscriber is enabled to transmit to 75

the exchange operator signals for example. It will be assumed that a connection has been established to subscriber $Tn2$ over the second group selector IIIGW, third group selector IIIGW and the final selector LW. This call can for example be set up with the collaboration of an exchange operator who can also effect the setting of the switches in question. The testing circuit between the second group selector IIIGW and the third group selector IIIGW is as follows: earth, battery, winding of relay C3, contact 44g1, wiper c of the second group selector IIIGW, winding I of relay P2, contact 42p2, rectifier G16, contact 43c2 and earth. The rectifier G15 is non-conductive to the current flowing in the above-mentioned circuit so that the entire current passes over winding I of relay P2. Rectifier G16 on the other hand is arranged in the opposite sense to rectifier G15 and constitutes a short-circuit for the winding of relay G2 so that for the moment this relay cannot energize. The testing circuit between the third group selector IIIGW and the final selector LW is as follows: earth, battery, winding I of relay C4, contact 49g, wiper c of the third group selector IIIGW, winding I of relay P3, contact 47p3, rectifier G18, contact 48c3 and earth. In this circuit only relays C4 and P3 are energized relay G1 being short-circuited by rectifier G18. The rectifier G17 which is arranged in the opposite sense to rectifier G18 is non-conductive to the current flowing in the circuit just mentioned so that the whole of the current passes over winding I of relay P3.

35 A relay G having two windings I and II is arranged in the final selector. The two windings are arranged differentially so that relay cannot energize at once when the subscriber $Tn2$ takes up his receiver.

40 If subscriber $In2$ wishes to transmit a signal to the exchange operator VB, he operates the key Ta . On account of the connection of earth over key Ta , the differential relay G is caused to energize. The closing of contact 51g prevents relay C4 from releasing. By the closing of contact 50g alternating current is applied to wiper c of the third group selector IIIGW over resistance W_{10} . On account of the connection of this alternating current relay G1 is energized in the 45 third group selector IIIGW and relay P3 is maintained energized over its winding I by the half-waves of the alternating current which do not pass through the rectifier G17. (Relay G1 is also energized by half-waves of alternating current which are actually those which do not pass through rectifier G18.) Relay G1 opens its contact 44g1 and closes its contact 45g1 and 46g1. Relay C3 is maintained energized at the last mentioned contact whilst at contact 45g1, alternating current is connected to wiper c of the second group selector IIIGW over resistance W_{19} , the direct current potential being disconnected. On account of this connection of alternating current relay G2 in the second group selector IIIGW 50 is energized by the alternating half-waves of alternating current which do not pass through rectifier G15. Relay G2 in the second group selector IIIGW is thus energized synchronously with the closing of key Ta by the subscriber $In2$ and is deenergized again on the opening of the key accordingly. Contact 41g2 is closed and opened a corresponding number of times at the exchange operator's position and thus operates lamp L. The subscriber $In2$ can thus signal the exchange operator in this way.

Here again the release operations are of no special significance so that they will not be described in detail.

By the application of earth at the subscriber's station $In2$, other operations can also be effected, for example, another relay could be operated by relay G2 serving to "seize" the calling subscriber to form a protection against false calls.

Fig. 3 shows an arrangement which enables different traffic directions to be controlled by the application of the invention. A preselector VW is shown over which a number of traffic directions, for example RI and RII may be reached. The following circuit is established for the rotary magnet D2 of the preselector: earth, battery, rotary magnet D2, contacts 61c5 and 62p4, relay interrupter RU2 and earth. The preselector is stepped by means of the relay interrupter until it has found a free line in the direction RI. The following testing circuit is then set up from earth, battery, winding of relay C6, contact 72dk, wiper c of the preselector VW, rectifier G19, contact 67h1, winding of relay P4, high resistance W_{13} , contact 71c5 and earth. In this circuit the testing relay P4 and the seizing relay C6 of the connecting device arranged beyond the preselector, energize. Relay P4 closes contact 70p4 and by short-circuiting the high resistance W_{13} guards the next connecting device which has been seized. At contacts 59p4 and 60p4 it switches through the speaking leads in the known way. The rectifier G19 is arranged so that it is conductive to the normal testing and guarding current and thus constitutes a short-circuit for the winding of relay U. The rectifier G10 is arranged in the opposite sense to rectifier G19 so that the whole of the current passes over the winding of relay P4. Contact 73dk is only closed when the switching device following the preselector, for example, the first group selector IGW is raised to a definite level, for example, level 10. If the first preselector IGW arranged beyond the preselector VW is set on one of the levels 1-9 by the calling subscriber contact 72kd 45 remains closed and there is no switching over on to the direction RII. The setting of the connecting device and the establishment and release of the connection take place in the known manner and are of no particular interest.

If, however, after the preselector VW has been set on the direction RI an impulse train consisting of 10 impulses is transmitted by the calling subscriber, contact 72dk is opened in the first group selector and contact 73dk is closed. The seizing relay C6 is caused to deenergize by the opening of contact 72dk and the release of the first group selector which occurs shortly afterwards takes place in the known way. On account of the closing of contact 73dk alternating current is applied to wiper c of the preselector VW over resistance W_{11} . Relay U in the preselector VW is accordingly energized by the alternate half waves of alternating current which do not pass through the rectifier G19, whilst relay P4 60 is similarly held up for the time being. Relay U closes its contact 64u and thereby completes the following circuit for relay H1: earth, battery, winding of relay H1, contacts 64u, 65c5, and earth. Relay H1 energizes in this circuit, establishing a locking circuit for itself by closing its contact 63h1 and at contacts 66h1 short circuits the winding of relay U so that this relay falls back after a short time. In addition relay H1 65 opens its contact 69h1 and thereby disconnects 70

75

the rectifier G10 arranged in parallel with the winding of relay P4. It also opens its contact 67h1 and closes contact 68h1, thereby the rectifier G9 which previously was arranged in the 5 opposite sense to the rectifier G10 is now connected in parallel with the winding of relay P4. Since now the rectifier G9 is conductive to those alternate half waves which are not transmitted by rectifier G10 a reversal of polarity is effected 10 in the winding of relay P4 which causes it to release. Relay P4 closes its contact 62p4 and thereby completes the circuit for the rotary magnet D2 of the preselector VW. The preselector is stepped round by the action of the relay interrupter RU2 and hunts for a free line in the direction RII. When such a line has been found the 15 following testing circuit is established: earth, contact 71c5, high resistance Wi13, winding of relay P4, contact 66h1 and in parallel contact 20 68h1 and rectifier G9, wiper c of the preselector VW, seizing relay C7 and in parallel thereto rectifier G11, resistance Wi12, and source of alternating current. In this circuit relay P4 energizes on account of the alternate half waves of 25 alternating current which do not pass through the rectifier G9 and this relay by opening its contact 62p4 brings the preselector to rest. By means of the short-circuit over the high resistance Wi13 at contact 70p4 the free connecting 30 device which has been found in the traffic direction RII is guarded against further seizure.

In this case, that is, in the case of calls in the direction RII testing and guarding are effected by means of alternating current.

35 In this case also the operations for the further setting up of the call and for the release of the call are of no special significance so that no explanation of these operations will be given.

What is claimed is:

40 1. In a telephone system, a test circuit over which two different switching operations are controlled, a test relay and a control relay included in said test circuit, a rectifier shunting each of said relays, one of said rectifiers poled in the opposite direction from the other, a source of direct 45 current, a source of alternating current, means for connecting either said direct current source or said alternating current source to said test circuit, said rectifiers effective to cause said test circuit to operate to control one of said switching operations when said direct current source is connected, and effective to cause said control relay to operate to control the other of said switching operations when alternating current is 50 connected.

55 2. A system as claimed in claim 1, in which the rectifier shunting the test relay is non-conductive to direct current flow and the rectifier shunting the control relay is conductive to direct current flow and thereby short-circuits the control relay.

60 3. A system as claimed in claim 1, in which the direct current for operating said test relay is disconnected during the time that said test and said control relays are operated by the alternating current.

65 4. A system as claimed in claim 1, in which a timing device associated with the test circuit of said switch is adapted to momentarily apply said alternating current to said test circuit at predetermined intervals and in which a magnet associated with a calling subscriber's line circuit is operated responsive to each operation of said control relay.

70 5. In a telephone system, a plurality of automatic switches controlled from a calling sub-

scriber's line for establishing a telephone connection, a test circuit for each of said switches, a test relay and a control relay included in each of said test circuits, a source of direct current for operating each of said test relays in turn as the call progresses, a timing device associated with the test circuit of the last switch for momentarily applying alternating current thereto at predetermined intervals to operate the control relay associated with the last switch, means responsive to the operation of any control relay for applying alternating current to the test circuit of the preceding switch to operate the associated control relay, line equipment individual to the calling subscriber's line, and means responsive to the operation of the control relay of the first switch for controlling the operation of a magnet associated with said line equipment.

75 6. In a telephone system, a test circuit over which two different switching operations are controlled, a test relay and a control relay included in said test circuit, a rectifier shunting each of said relays, one of said rectifiers poled in the opposite direction from the other, a source of direct current, means for connecting said direct current source to said test circuit to operate said test relay, means responsive to the operation of said test relay for controlling one of said switching operations, said control relay shunted by its associated rectifier when said direct current is connected to said test circuit, a source of alternating current, means for connecting said alternating current source to said test circuit to operate said control relay, and means responsive to the operation of said control relay for controlling the other of said switching operations, each rectifier shunting its associated relay on one-half of each cycle of alternating current and preventing the shunting of its associated relay on the other half of each cycle of alternating current.

80 7. In combination, a first and second relay in a series circuit, a rectifier associated with each of said relays for permitting current of one polarity but not of the other to flow through said first relay and for permitting current of the second polarity but not of the first to flow through said second relay, means for applying direct current of one polarity to said series circuit to energize said first relay, means for applying alternating current to said series circuit to maintain said first relay energized and to energize said second relay; means responsive to the energization of said second relay for releasing both of said relays and for altering said series circuit so that the rectifier associated with said first relay is disconnected therefrom, the rectifier associated with said second relay is disconnected therefrom and associated with said first relay, and said second relay is shunted to prevent energizing; and means for again applying alternating current to said altered circuit to again energize said first relay.

85 8. In combination, two relays in a series circuit, a rectifier associated with each of said relays for permitting current of one polarity but not of the other to flow through one relay winding and for permitting current of the second polarity but not of the first to flow through the second relay winding, means for applying direct current of one polarity to said series circuit to energize one of said relays, means for applying alternating current to said series circuit to maintain said one relay energized and to energize the other of said relays, means responsive to the operation of the other of said relays for releas-

ing both of said relays and for altering said series circuit, and means for again applying alternating current to said altered series circuit to again energize the said one of said relays previously energized by direct current.

5 9. In a circuit arrangement, an automatic switch adapted to extend a connection therethrough, a test relay, a control relay, a rectifier shunting each one of said relays, a test circuit for said switch including said test relay and said control relay, means for applying direct current to said test circuit to operate said test relay, said rectifiers being oppositely poled so that said test relay operates and said control relay is shunted when said direct current is connected to said test 10 circuit, means for applying alternating current to said test circuit to maintain said test relay energized and to energize said control relay, said rectifiers effective to prevent the release of said relays on alternate half-cycles of alternating current.

15 10. In combination, an automatic switch, means for extending a connection therethrough, said switch having a test relay and a control relay, a rectifier bridging each of said relays, a source of direct current, a source of alternating current, means for connecting said source of direct current to said relays, said rectifiers associated with said relays so poled that application 20 of direct current thereto causes only the test relay to operate, means for changing said connecting means from said source of direct current

to said source of alternating current to maintain said test relay energized and to cause said control relay to operate.

11. In an automatic circuit arrangement, an automatic switch, a test circuit associated therewith for controlling different switching operations thereof, said circuit including a test relay, a control relay, and shunting rectifiers for each of said relays, a source of direct current connected to the test circuit for operating said test 10 relay to control a switching operation, the rectifier shunting said test relay poled so that it is non-conductive to the direct current and the rectifier shunting the control relay poled so that it is conductive to direct current and short circuits 15 said control relay, a source of alternating current, means for disconnecting said source of direct current and for connecting said source of alternating current, said alternating current maintaining said test relay energized and completing an energizing circuit for said control 20 relay, and means responsive to the operation of said control relay to control a second switching operation.

25 12. An automatic telephone system as claimed in claim 11, in which said second switching operation causes the release of said test and control relays and said test relay then reoperates responsive to a second connection to said alternating current source to control a third switching 30 operation.

HERBERT TÖPFER.
